UNITED STATES PATENT OFFICE.

FRANK P. LITZ, OF CORRY, PENNSYLVANIA.

FOOT REST.

Application filed April 29, 1922. Serial No. 557,391.

To all whom it may concern:

Be it known that I, FRANK P. LITZ, a citizen of the United States, and a resident of Corry, in the county of Erie and State of Pennsylvania, have invented certain new and useful Improvements in Foot Rests, of which the following is a specification.

This invention relates to an improvement in foot rests for use with boot-black stands or the like.

The object of the invention is to provide a foot rest which is adjustable and removable whereby when the foot rest is not in use it may be removed or adjusted so that it will not afford an obstruction and projection liable to catch and tear the clothes of a person using the foot rest or impede or obstruct the movements of a person in stepping up upon or leaving the stand upon which the foot rest is mounted.

Another object is to provide a foot rest of this character which is of extremely simple and durable construction, which when in position is positively supported and firmly held against undesirable movements, which may be readily associated with ordinary types of boot-black stands and which is easy and comparatively inexpensive to manufacture.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a perspective view, illustrating the foot rest in operative position upon a boot-black stand;

Figure 2 is a detail view of the foot rest in side elevation, parts being shown in section for the sake of illustration;

Figure 3 is a detail perspective view, illustrating the construction of the swivelled bracket and the cooperating structure of the arm of the foot rest.

Referring to the drawings, the numeral 10 designates a boot-black stand which may be of any conventional type or construction and which includes a platform 11 upon which the foot rests as well as the chairs or seats are mounted.

As shown in Figure 1, the foot rests which constitute the present invention are provided in pairs but as all of the foot rests are of

identical construction, a description of one will serve for all. Each comprises a swiveled bracket 12, the bracket being swiveled upon the platform 11 by a bolt 13 or the like, and if desired anti-friction means such as ball bearings or the like may be interposed between the bolt and the bracket. The bracket is hollowed out and the base of the cavity in the bracket which is thus formed is provided at its forward end with a seat 14 and at about the center of the bracket a cross bar 15 is provided and is integrally formed with the side walls of the cavity of the bracket and extends across and between the same, as shown in the drawings.

An arm 16 is provided and is notched at one end, as at 17, and this notched end is adapted to be received in the cavity of the bracket in which position the cross bar 15 of the bracket is received in the notch 17 of the arm and the underside of the notched end of the arm is received and supported upon the seat 14, the side walls of the arm snugly engaging the side walls of the cavity of the bracket. The outer end of the arm 16 carries a foot plate 18, the foot plate being preferably formed integral with the outer bifurcated end of the bracket.

It is obvious that the arm 16 which carries the foot plate may be readily removed or taken from the bracket by tilting the arm upwardly until the cross bar 15 and the notch 17 are disengaged, there being sufficient clearance between the inner end of the arm 16 and the bottom wall of the cavity of the bracket to permit of this motion. The arm carrying the foot plate may also be readily introduced into the cavity of the bracket by inserting the notched end thereof into this cavity and working the notch 17 up under the cross bar 15 by a downwardly tilting or swinging motion.

When the arm 16 is removed from the bracket there is of course no obstruction in the way of a person stepping upon or leaving the stand and liable to engage and tear his clothes or otherwise interfere with them. In lieu of entirely removing the arms from the brackets, the arms may be readily swung horizontally to a position out of the way by virtue of the fact that the brackets 12 are swivelled upon the platform. In conjunction with the swivelling of the brackets it is obvious that in lieu of mounting the brackets 12 directly upon the platform these brackets may be mounted upon bed plates

secured upon the platform and the brackets and plates may have raceways in which ball bearings are arranged in order to facilitate and render easy the turning movement of the brackets.

Means is provided to prevent turning movement of the bracket when the foot rest is in use. Preferably this means comprises an arcuate plate 20 secured to the platform 11 by screws 21 and having a plurality of series of sockets 22 with which a lug 23 integrally formed with the arm 16 of the foot rest is selectively cooperable. It is obvious that when the lug 23 is received in one of the sockets turning movement of the bracket 12 on its swivel is prevented whereby the arm of the foot rest and the foot plate which is carried by the arm is firmly and positively held to provide a rigid and stable support for the person using the foot rest. By providing a series of sockets the members of the pair of foot rests may be arranged parallel or may be arranged in the desired angular relation with respect to each other whereby the foot rest may be used with comfort by persons of various sizes, weights and builds.

I claim:

1. In a foot rest of the character described, a bracket having a cavity therein provided with a seat and having a cross bar extending between the side walls of said cavity, an arm having a notched end adapted to be received in the cavity of the swivelled bracket and to be supported upon the seat thereof, the cross bar of the bracket being adapted to be engaged with the notch of the arm, and a foot plate carried by said arm.

2. In a foot rest of the character described, a swivelled bracket having a cavity therein provided with a seat and having a cross bar extending between the side walls of said cavity, an arm having a notched end adapted to be received in the cavity of the swivelled bracket and to be supported upon the seat thereof, the cross bar of the bracket being adapted to be engaged with the notch of the arm, a foot plate carried by said arm, an arcuate plate having a series of sockets therein, and a lug carried

by the arm and selectively engageable with said sockets.

3. In combination with a platform, a bracket, means for swivelling the bracket upon the platform, an arm detachably connected with the bracket, a foot plate connected with said arm, and cooperating means between the arm and the platform for releasably securing the arm and the bracket against turning movement when the foot rest is in operative position.

4. In combination with a platform, a bracket, means for swivelling the bracket upon the platform, an arm detachably connected with the bracket, a foot plate connected with said arm, and cooperating means between the arm and the platform for releasably securing the arm and the bracket against turning movement when the foot rest is in operative position, including a plate secured upon the platform and having a series of sockets therein, and a lug connected to the arm and selectively engageable with the sockets.

5. In combination with a platform, a bracket and means for swivelling the bracket upon the platform, said bracket having a cavity provided with a seat, and a cross bar extending between the side walls of the cavity, an arm having a notched end receivable in the cavity and supported upon the seat with the notch of said arm engaging the cross bar of said bracket, a foot plate carried by said arm, and means for preventing turning of said arm when the foot rest is in operative position.

6. In a foot rest of the character described, a swivelled bracket, an arm connected with said bracket, a foot plate carried by said arm, a fixed plate having a socket and a lug carried by the arm and engageable with said socket.

7. In combination with a platform, a bracket swivelled thereon so as to be freely rotatable about a vertical axis, an arm connected to the bracket and extending outwardly therefrom, a foot plate carried by the outer end of the arm and releasable means for preventing turning movement of the arm and bracket.

FRANK P. LITZ.
